DESIGN FOR A ONE-PIECE UNIFORM

Frank H. Anderson, Birmingham, Ala.

Application September 29, 1934, Serial No. 53,435

Term of patent 14 years

To all whom it may concern:

Be it known that I, Frank H. Anderson, a citizen of the United States, residing at 2112 Eleventh Court, South, city of Birmingham, in the county of Jefferson and State of Alabama, have invented a new, original, and ornamental Design for One-Piece Uniforms, of which the following is a specification, reference being had to the accompanying drawing, forming part thereof, in which:

Fig. 1 is a front view of the uniform; and
Fig. 2 is a side view of the uniform.

Referring now to the drawing, I show a one-piece uniform comprising a trouser portion 1, a shirt portion 2 and a belt 3. The straight front portion, belt and full bulging rear portion of the garment immediately above the belt comprise the essential features of my design.

I claim:

The ornamental design for a one-piece uniform, substantially as shown and described.

FRANK H. ANDERSON.
